W. D. ALLEN

ENAMELING APPARATUS

Filed May 23, 1924

Inventor:
Will Dean Allen.
by Right from County May
attys.

UNITED STATES PATENT OFFICE.

WILL DEAN ALLEN, OF FARMINGTON, NEW HAMPSHIRE.

ENAMELING APPARATUS.

Application filed May 23, 1924. Serial No. 715,454.

To all whom it may concern:

Be it known that I, WILL DEAN ALLEN, a citizen of the United States, residing at Farmington, in the county of Strafford and 5 State of New Hampshire, have invented new and useful Improvements in Enameling Apparatus, of which the following is a specification.

The object of this invention is to provide 10 means whereby a large number of racks supporting articles, such as wooden brush handles, and adapted to be dipped in liquid enamel to coat the supported articles, may be supported and moved in a drying space 15 or chamber while the articles are being dried, a particular object being to enable two operators to work simultaneously and rapidly, manipulating the racks to first coat the articles thereon, and then progressively 20 move the racks through a space in which the enamel is dried, and finally, removing the dried articles.

The preferred form of the apparatus embodying the invention comprises a drying 25 chamber through which heated air is circulated, two substantially horizontal runways extending from end to end of the chamber, each runway being adapted to support a procession of racks and dipping tanks 30 located at opposite ends of the chamber, the arrangement being such that two operators, one at each end of the chamber, may work simultaneously, each operator dipping racks successively in a tank, pushing the dipped 35 racks along one runway toward the other operator, and removing other racks pushed along the other runway by the other operator.

Of the accompanying drawings forming a 40 part of this specification,—

Figure 1 is a longitudinal vertical section of an apparatus embodying the invention.

Figure 2 is a section on line 2—2 of 45 Figure 1.

Figure 3 is a fragmentary perspective view, showing a portion of one end of the chamber and a portion of one of the runways.

Figure 4 is a perspective view of one of 50 the racks shown by Figures 1 and 2.

The same reference characters indicate 55 the same parts in all of the figures.

The drying chamber shown by the drawings includes side walls 12, end walls 13,

and a top 140, these being preferably of sheet metal. The end walls are provided with transverse openings 15. The chamber is provided with two substantially horizontal runways extending from end to end of 60 the chamber, one being a lower runway extending continuously between the openings 15, and the other an upper runway extending continuously between said openings. 65 Each runway may be conveniently formed by a pair of angle bars 14, constituting track members secured to the side walls 12. Said members preferably project through the openings 15, as best shown by Figure 3.

Associated with the drying chamber are 70 two dipping tanks 16, containing liquid enamel. The tanks are located outside of and adjacent to the end walls 13 and below the projecting ends of the runways.

The racks are preferably constructed as 75 shown by my Patent No. 1,452,821, dated April 24, 1923, each being an open frame or grid, composed of spaced apart parallel bars 17 (Figure 4), having upwardly projecting 80 holders 19, with which articles 20 to be 85 enameled are engaged. The end portions of the racks are adapted to slide on the runways, the major portions of the racks being exposed between the runway members, so that the articles thereon are surrounded by 90 heated air rising in the chamber.

The apparatus thus described may be used 95 by two operators, one at each end of the chamber, the operators being in position to insert racks into the tanks. The operators 100 work simultaneously, each operator dipping racks successively into one of the tanks and depositing the racks successively on the projecting ends of the members of one runway.

The surplus enamel dripping from 105 each rack thus deposited, and from the articles thereon, drops into the tank below it, the tank being preferably provided with an inclined apron 22, arranged to guide some of the drippings into the tank. The 110 operator when depositing a rack on the runway members, and pushing it toward the chamber, causes the rack to push another rack or racks previously deposited, until there is a procession of racks extending the entire length of the runway. The arrows

x, x, (Figure 1) indicate the direction of movement of the racks controlled by an operator at the left hand end of the chamber. The operator at the right hand end 110

dips racks in the corresponding tank, deposits the racks on the members of the other runway, and pushes the racks in the direction of the arrows y, y . Each operator successively removes the racks pushed toward him and, in case the articles on these racks have not been sufficiently coated, the operator dips the racks again, deposits them on his runway, and causes them to again pass through the chamber. Emerging racks carrying articles which have been sufficiently coated, are laid aside by the receiving operator.

The length of the chamber and runways is such that during a single pass of a rack through the chamber, the coatings on the articles carried by the rack, are sufficiently dried, means being preferably provided, as described hereinafter, for causing a circulation of heated air through the chamber in contact with the coated articles.

I prefer to provide means under the receiving end portions of the runways for removably supporting drip pans 24 in position to catch any drip which is not caught by the accompanying tank 16, said means in this instance, being angle bars 25, secured to the side walls 12 below the bars 14, constituting track members communicating with the openings 15, so that the drip pans may be removed through said openings to pour the enamel collected therein into the tanks 16.

It is obvious that the invention may be embodied in an apparatus including a chamber having only one runway, the racks emerging from this runway, and carrying articles which have been coated once, being removed and laid aside. It is usually desirable, however, to coat the articles two or more times. Any number of coatings may be applied by the two operators working simultaneously, as above described.

The chamber is preferably provided below the runways with heating means, adapted to heat air admitted through inlets 26 in the lower portion of the chamber, the heating means here shown being a steam coil 27.

To induce an effective upward movement of the heated air, I provide a horizontal partition 28, spaced from the top 140, by an exhaust chamber 30, and having openings 31. The top 140 communicates with a draft inducing flue or stack 32.

I claim:

1. An enameling apparatus comprising a drying chamber including side walls and end walls, the end walls being provided with transverse openings, a substantially horizontal rack-guiding runway composed of spaced apart track members extending continuously between said openings and formed to guide the end portions of enameling racks bridging the space between the

track members, the arrangement being such that an operator at one end of the chamber may deposit racks successively upon said tracks at one end of the runway, and push the racks in a procession through the chamber for removal at the opposite end, and spaced apart tracks arranged to support a drip pan below the runway in position to receive enamel dropping from the racks last deposited, and to permit the insertion and removal of the pan through an end wall opening.

2. An enameling apparatus comprising a drying chamber including side walls and end walls, the end walls being provided with transverse openings, a substantially horizontal lower runway composed of spaced apart track members extending continuously between said openings, and a substantially horizontal upper runway also composed of spaced apart track members, extending continuously between said openings, the track members of each runway being formed to guide the end portions of enameling racks bridging the space between said members, the arrangement being such that two operators, one at each end of the chamber, may work simultaneously, each operator depositing racks successively on one end of a runway, and pushing the racks in a procession toward the other operator.

3. An enameling apparatus comprising a drying chamber including side walls and end walls, the end walls being provided with transverse openings, a substantially horizontal lower runway composed of spaced apart track members extending continuously between said openings, a substantially horizontal upper runway also composed of spaced apart track members, extending continuously between said openings, the track members of each runway being formed to guide the end portions of enameling racks bridging the space between said members, and dipping tanks located outside the chamber, below the ends of the runways, the arrangement being such that two operators, one at each end of the chamber, may work simultaneously, each operator dipping racks successively in a tank, depositing the dipped racks successively on one end of a runway, pushing the racks in a procession toward the other operator, and removing other racks pushed along the other runway by the other operator.

4. An enameling apparatus comprising a drying chamber having two substantially horizontal runways extending through the chamber, and dipping tanks located at opposite ends of the chamber, the runways projecting from opposite ends of the chamber and overhanging the tanks, so that enamel dripping from articles on the overhanging portions of the runways is received by the tanks.

5. An enameling apparatus comprising a drying chamber, having a substantially horizontal runway extending from end to end of the chamber, air-heating means below the runway, air inlets below the heating means, a partition above the runway and below the chamber top forming the bottom of an ex- haust chamber, said partition having air openings, and an outlet communicating with the exhaust chamber. 10
- In testimony whereof I have affixed my signature.

WILL DEAN ALLEN.
